RAILWAY SIGNALING SYSTEM

George R. Pflasterer, Greenville, Pa., assignor to
The Union Switch and Signal Company, Swiss-
vale, Pa., a corporation of Pennsylvania

Application January 14, 1942, Serial No. 426,745

6 Claims. (Cl. 246—33)

My invention relates to railway traffic controlling apparatus, and particularly to signaling apparatus for governing the movement of traffic over stretches of single track over which traffic moves in both directions.

It is an object of my invention to provide a system of the type described and incorporating means to prevent the headblock signal governing movement of traffic into the single track stretch between two passing sidings from displaying its clear indication when a train moving in the other direction is approaching the other end of the single track stretch.

A further object of my invention is to provide a signaling system of the type described which is arranged so that two trains approaching a single track stretch simultaneously will not both receive clear signal indications from the signals at the entrance ends of the single track stretch.

Another object of my invention is to provide an improved signaling system of the type described which is arranged so that no more line wires are required than are needed in the systems heretofore employed.

Other objects of the invention and features of novelty will be apparent from the following description taken in connection with the accompanying drawings.

In practicing my invention I provide line circuits coextensive with the single track stretch between two passing sidings and employ direct current in these circuits to control the signals governing traffic in both directions in this track stretch. In addition, I provide means to supply alternating current over the line wires for the signals for each direction of traffic and have means responsive to this energy for controlling the clear aspects of the signals governing entrance of trains into the single track stretch. The supply of alternating current to the line circuit for the signals for each direction of traffic is controlled so that the supply of this energy is cut off when a train traveling in the opposite direction approaches the end of the single track stretch to thereby prevent the display of a clear indication by the signal governing entrance of trains moving in the other direction in the single track stretch.

I shall describe one form of railway signaling system embodying my invention, and shall then point out the novel features thereof in claims.

In the drawings Figs. 1A and 1B when placed together with Fig. 1B at the right form a diagram

of a stretch of railway track equipped with signaling apparatus embodying my invention.

In order to simplify the drawings and to enable the circuits to be more readily traced I have identified each signal by a letter and number, and each relay by a letter or combination of letters with a distinguishing prefix identifying the signal with which the relay is associated.

Furthermore, instead of showing the sources of current for energizing the various line and local circuits I have shown only the terminals of these sources. The terminals of the sources of direct current are designated B and C, while the terminals of the sources of alternating current are designated BX and CX. The direct current may be provided by batteries, while the alternating current may be supplied from a commercial source of power and distributed throughout the track stretch by a transmission line, not shown.

Referring to the drawings, the reference characters 1 and 2 designate the track rails of a stretch of single track over which traffic may move in either direction.

For purposes of illustration it will be assumed that the left-hand end of the track stretch is west, and that the right-hand end thereof is east so that train movements from left to right are eastbound, and train movements from right to left are westbound.

The track rails are divided by insulated joints into track sections designated T with a distinguishing prefix. Each section is provided with a track circuit comprising the usual track battery connected across one end of the section rails, and a track relay, designated TR with an appropriate prefix, connected across the other end of the section rails.

The ends of the non-track circuited passing sidings PS are connected with the main track by track switches W.

The headblock signal 2S governs traffic on the main track moving from left to right across the switch 2W at the right-hand end of the passing siding 1PS into the adjacent single track stretch, while the headblock signal 1S governs traffic on the main track moving from right to left across the switch 1W at the left-hand end of the passing siding 2PS into the adjacent single track stretch.

The spacing of trains moving in the same direction through the single track stretch is governed by signals 4S, 6S and 8S, or by signals 5S, 3S and 1S, depending on the direction of

movement, as will be apparent from the drawings.

As shown, the signals are of the color light type, and each has an upper portion including a green or clear lamp G, a yellow or caution lamp Y, and a red or stop lamp R. The signals 1S and 8S may have other portions, not shown, for governing movement of traffic into the passing sidings.

The signals associated with the switches may be governed in accordance with the position of the switches in the manner well known in the art. This control of the signals by the switches is not a part of this invention, and has been omitted to simplify the disclosure. Similarly the supply of energy to the relays 1H and 8H which govern the signals 1S and 8S may be controlled by traffic or other conditions in advance of these signals in any manner well known in the art. The control of the supply of energy to these relays is not a part of this invention and has been omitted in order to simplify the disclosure.

Each signal has associated therewith a polarized relay H, which is preferably of the retained neutral type, while the windings of these relays are of such high impedance as to substantially prevent flow of alternating current therein.

The signals each have a directional stick relay SR associated therewith, while the signals 2S and 7S have relays J associated therewith which are energized when alternating current is supplied thereto from the other end of the single track stretch as hereinafter explained.

In most instances the relay contacts are shown directly under the relay with which they are associated, but in some cases in order to simplify the drawings relay contacts are shown separated from the relay, and where this is done the relay with which the contacts are associated is indicated by appropriate reference characters placed directly above the relay contacts.

The equipment is shown in the condition which it assumes when the track stretch is vacant, and the switches 2W and 7W are in their normal positions in which they direct traffic along the main track.

As the track stretch is vacant, energy is supplied to relay 8H by means not shown and the neutral contacts of this relay are picked up. As relay 8H is energized, its contacts 10 and 11 are picked up so that direct current of normal polarity is supplied over the line circuit consisting of line wire 14 and common wire 15 to relay 6H so that the neutral contacts of this relay are picked up and the polar contacts of the relay are in their normal positions and contacts 17 and 18 of the relay establish the circuit of the green lamp G of signal 8S.

In addition, contacts 20 and 21 of relay 6H cause direct current of normal polarity to be supplied over the line circuit consisting of line wire 24 and common wire 25 to relay 4H so that its neutral contact 26 and its polar contact 27 cooperate to establish the circuit of the green or clear lamp G of signal 4S.

In addition, at this time contacts 28 and 29 of relay 4H cause direct current of normal polarity to be supplied over the line circuit consisting of wire 32 and common wire 33 to relay 2H so that its contacts 35 and 36 establish the circuit to supply energy to the green or clear lamp G of signal 2S over the circuit which includes front contact 37 of relay 2J.

As relay 8H is picked up, its contact 40 con-

ncts one terminal of the primary winding of transformer 8M to terminal BX of a source of alternating current, while the other terminal of this winding is connected to the other terminal of the source.

The secondary winding of this transformer is connected in series with line wire 14 and is of such low resistance as not to substantially reduce flow of direct current in this circuit. On the supply of alternating current 10 to the primary winding of transformer 8M energy is induced in the transformer secondary winding and is supplied over wires 14 and 15 to the primary winding of transformer 6N. The primary winding of this transformer is connected 15 across the wires 14 and 15 in multiple with the winding of relay 6H. The transformer primary winding is of such high resistance as to substantially prevent flow of direct current therein, while the winding of relay 6H is of such 20 high impedance as to substantially prevent flow of alternating current therein.

On the supply of alternating current to the primary winding of transformer 6N energy is induced in the transformer secondary winding 25 which is connected in series with line wire 24 and is of such low resistance as not to impair flow of direct current in the circuit of this line wire. Energy from transformer 6N is supplied over wires 24 and 25 to the primary winding of 30 transformer 4N which is connected across wires 24 and 25 in multiple with the winding of relay 4H. The primary winding of transformer 4N is of such high resistance as to substantially prevent flow of direct current therein, while the 35 impedance of the winding of relay 4H is so high as to substantially prevent flow of direct current therein.

The secondary winding of transformer 4N is included in series with line wire 32 and is of low 40 resistance to permit free flow of direct current therethrough. On the supply of alternating current to the primary winding of transformer 4N energy is induced in the transformer secondary winding and is supplied therefrom over the line circuit consisting of wire 32 and common 45 wire 33 to the primary winding of transformer 2N which is connected across line wires 32 and 33 in multiple with the winding of relay 2H. Energy from the secondary of the transformer 2N is supplied through a suitable rectifier to the relay 50 2J so that contact 37 of this relay is picked up and establishes the circuit of the green lamp G of signal 2S.

The equipment controlling the signals governing westbound traffic is similar to that just described for the signals controlling eastbound traffic.

The relay 1H is governed in any manner well known in the art by traffic or other conditions 60 in advance of signal 1S, and as the stretch is assumed to be vacant, the neutral contacts of this relay are picked up. Accordingly, contacts 40 and 41 of relay 1H cause direct current of 65 normal polarity to be supplied to the line circuit consisting of wire 43 and common wire 33, while contact 42 of relay 1H causes alternating current to be supplied to the primary winding of transformer 1M, the secondary winding of which is connected in series with line wire 43.

The direct current supplied to line wires 43 and 33 feeds to relay 3H so that its contacts 45 and 46 establish the circuit of the green lamp G of signal 3S, while contacts 48 and 49 of relay 3H cause direct current of normal polarity to be 70 supplied over the line circuit consisting of wire 75

50 and common wire 25 to relay 5H. Contacts 53 and 53 of relay 5H, therefore, establish the circuit of the green lamp G of signal 5S, while contacts 54 and 55 of relay 5H cause direct current of normal polarity to be supplied over the line circuit consisting of wire 57 and common wire 15 to relay 1H so that its contacts 59 and 60 establish the circuit to permit energy to be supplied to the green lamp G of signal 1S.

The alternating current supplied to transformer 1M is supplied therefrom through transformers 3N and 5N to transformer 7N from which it is supplied through a rectifier to relay 7J so that its contact 61 is picked up and establishes the circuit of the green lamp G of signal 7S.

The primary windings of the transformers 3N, 5N and 7N are of such high resistance as to substantially prevent flow of direct current therein, while the secondary windings of transformers 1M, 3M and 5M are of low resistance so as to permit free flow of direct current therethrough. The windings of relays 3H, 5H and 7H are of such high impedance as to substantially prevent flow of alternating current therein.

From the foregoing it will be seen that when the track stretch is vacant, the signals governing movement of traffic in each direction through the single track stretch are conditioned to display their green or clear indications. In addition, as the portions of the main track adjacent the passing sidings are vacant, alternating current is supplied from the passing siding at either end of the single track stretch to the relay J at the other end of the single track stretch to thereby condition the associated headblock signal to display a green or clear indication.

Operation of equipment on passage of an eastbound train through the track stretch

When an eastbound train enters the portion of the track stretch within the control limits of relay 1H, the circuit of this relay is interrupted and the relay contacts release so that contact 64 interrupts the pick-up circuit of the directional stick relay 1SR. The control of relay 1H is arranged so that the circuit of this relay is interrupted before the train enters section 1T and releases relay 1TR to thereby insure that the contact 64 of relay 1H interrupts the pick-up circuit of relay 1SR before this circuit is established by contact 63 of relay 1TR.

At this time, therefore, contact 65 of relay 1SR remains released and interrupts the circuit controlled thereby for supplying energy to transformer 1M. On release of the contacts of relay 1H its contact 42 interrupts the supply of alternating current to transformer 1M, with the result that energy is no longer supplied therefrom through transformers 3N, 5N and 7N to relay 7J, and contact 61 of this relay releases and interrupts the circuit of the green lamp G and establishes the circuit of the yellow lamp Y of signal 7S.

It will be seen, therefore, that as soon as an eastbound train enters the control limits of relay 1H, the headblock signal at the other end of the single track stretch is caused to display its yellow or caution indication instead of its green indication so that a westbound train approaching the other end of the single track stretch will be notified of the approach of the eastbound train and will reduce its speed before entering the single track stretch.

In like manner, when a westbound train enters the portion of the track stretch within the con-

trol limits of relay 8H, contact 40 of this relay cuts off the supply of alternating current to transformer 8M, and thereby causes release of relay 2J so that its contact 37 interrupts the circuit of the green lamp G and establishes the circuit of the yellow lamp Y of signal 2S, so that an eastbound train will reduce its speed before entering the single track stretch.

When the eastbound train under consideration advances into section 2T, track relay 2TR releases and its contact 66 interrupts the supply of energy to relay 2H and to transformer 2N, and thus to relay 2J. Accordingly, contact 35 of relay 2H releases and establishes the circuit of the red or stop lamp R of signal 2S. In addition, on release of the track relay 2TR its contact 67 interrupts the supply of direct current to the circuit of line wires 43 and 33, while it establishes connection between these wires so that on the supply of alternating current to the primary winding of transformer 1M energy will be supplied from the transformer secondary winding over wires 43 and 33.

On release of contact 67 of track relay 2TR and interruption of the supply of direct current energy to line wires 43 and 33, relay 3H releases and its contact 45 establishes the circuit of the red light R of signal 3S. In addition, on release of relay 3H its contacts 48 and 49 cut off the supply of direct current to wires 50 and 35, while contact 69 of relay 34 interrupts the pick-up circuit of relay 3SR so that the contacts of relay 3SR remain released and its contact 70 interrupts connection from terminal B of the source of direct current to back contact 48 of relay 3H. Accordingly, after release of relay 34 direct current energy is no longer supplied to the line circuit consisting of wires 50 and 25, and relay 5H releases so that its contact 52 establishes the circuit of the red lamp R of signal 5S.

In addition, on release of relay 5H its contacts 54 and 55 cut off the supply of direct current to the circuit of wires 57 and 15, while its contact 72 interrupts the circuit of relay 5SR so that contact 73 of relay 5SR remains released and interrupts connection from terminal B to back contact 54 of relay 5H with the result that the supply of direct current to line wires 57 and 15 is cut off when relay 5H releases.

As the supply of energy to line wires 57 and 15 is cut off, contact 59 of relay 1H releases and establishes the circuit of the red lamp R of signal 1S.

It will be seen, therefore, that the system is arranged so that as soon as the eastbound train advances beyond the end of the passing siding 1PS and enters section 2T, all of the westbound signals up to and including the headblock signal 1S at the leaving end of the passing siding 2PS are placed at stop so that a westbound train will not enter the single track stretch.

When the eastbound train advances into section 3T, track relay 3TR releases and additionally interrupts the line circuits consisting of wire 32 and common wire 33, and of wire 43 and common wire 33.

When the train advances into section 4T, track relay 4TR releases and its contact 75 interrupts the circuit of relay 4H so that contact 26 of this relay releases and establishes the circuit of the red lamp R of signal 4S. At this time contact 76 of relay 4TR interrupts line wire 50, but as energy is not being supplied over this wire at this time release of the contact 76 is without effect.

On release of track relay 4TR its contact 17 establishes the pick-up circuit for relay 4SR. This circuit also includes front contact 78 of relay 4H and is interrupted as soon as this contact releases. As the relay 4H is of the retained neutral polar type, its neutral contacts remain picked up for a short period subsequent to interruption of the supply of energy to the relay winding, and during this period the contacts of relay 4SR pick up so that its contact 19 establishes a stick circuit to maintain the relay energized after release of relay 4H. On release of contact 78 of relay 4H it establishes connection with terminal B of the source so that thereafter relay 4SR is maintained energized as long as either relay 4TR or relay 4H is released.

As relay 4SR is energized, its contact 80 is picked up and establishes connection from terminal B to back contact 28 of relay 4H, while back contact 29 of relay 4H establishes connection from terminal C so that direct current of reverse polarity is supplied to line wires 32 and 33.

When the train advances into section 5T, track relay 5TR releases and additionally interrupts the line circuits formed by wire 50 and common wire 25, and by wire 24 and common wire 25.

When the train advances into section 6T, track relay 6TR releases and its contact 81 interrupts the circuit of relay 6H, while its contact 82 interrupts the circuit of line wire 57, and its contact 83 establishes the pick-up circuit including front contact 85 of relay 6H for energizing relay 6SR so that contact 86 of this relay establishes a stick circuit to maintain the relay energized after release of relay 6H.

On release of relay 6H its contact 17 establishes the circuit of the red lamp R of signal 6S, while its contacts 20 and 21 establish the circuit including front contact 88 of relay 6SR for supplying direct current of reverse polarity to the circuit of line wires 24 and 25.

When the train advances into section 7T, track relay 7TR releases and additionally interrupts the circuits formed by wires 14 and 57 and the common wire 15.

On release of track relay 7TR its contact 89 interrupts connection from line wire 14 to contact 11 of relay 8H, while it establishes connection between wires 14 and 15 so that the secondary winding of transformer 8M is connected directly across the wires 14 and 15 instead of being connected across these wires in series with the source of direct current. Accordingly, alternating current may be supplied from transformer 8M over line wires 14 and 15 to the primary winding of transformer 6N. However, as long as relay 5TR is released, its contact 101 interrupts wire 24 so that energy is not supplied from transformer 6N to transformer 4N.

When the train advances into section 8T, track relay 8TR releases and its contact 90 establishes the pick-up circuit including front contact 91 of relay 8H for energizing relay 8SR so that the contacts of relay 8SR pick up and its contact 92 establishes a stick circuit to maintain the relay energized after release of relay 8H.

On release of track relay 8TR its contact 94 interrupts the circuit of relay 8H so that contacts 10 and 11 of relay 8H release and cause the direct current supplied to the circuit of line wires 14 and 15 to be of reverse polarity, while contact 40 of relay 8H interrupts one circuit for supplying alternating current to transformer 8M and establishes the circuit including front contact 95 of

relay 8SR for supplying alternating current to this transformer.

When the rear of the train vacates section 1T, track relay 1TR picks up and establishes the circuit of relay 1H, while its contact 63 interrupts one connection from terminal B of the source to a terminal of the winding of relay 1SR. On picking up of the relay 1H its contact 64 interrupts the connection controlled thereby from terminal 10 B to the winding of relay 1SR so that relay 1SR remains deenergized.

On picking up of relay 1H its contacts 40 and 41 establish connections to supply direct current of normal polarity to wires 43 and 33, but at this 15 time the supply of direct current to these wires is prevented by contact 67 of relay 2TR which is released.

On picking up of the contacts of relay 1H its contact 42 establishes a circuit to supply alternating current to the primary winding of transformer 1M so that current is induced in the transformer secondary winding. As contact 67 of relay 2TR is released, connection is established from one terminal of the transformer secondary 25 winding to common wire 33, while the other terminal of this winding is connected to wire 43. Accordingly, alternating current from the transformer 1M is supplied over wires 43 and 33 to the primary winding of transformer 3N. However, at this time contact 76 of relay 4TR 30 interrupts the circuit of the secondary winding of transformer 3N so that energy is not supplied beyond this transformer.

When the train vacates section 2T, track relay 35 2TR picks up and its contact 67 connects the secondary winding of transformer 1M across the line wires 43 and 33 in series with the battery from which direct current is supplied to this circuit, while contact 66 of relay 2TR is picked up 40 to permit energy to be supplied to relay 2H.

When the train vacates section 3T, track relay 3TR picks up and its contact 97 establishes the circuit to permit energy to be supplied to relay 3H and the contacts 45 and 46 of this relay establish the circuit of the green or clear lamp G of signal 3S, while contacts 48 and 49 of relay 45 3H are picked up to establish the circuits to supply direct current of normal polarity to wires 50 and 25.

On picking up of contact 98 of relay 3TR the 50 circuit for supplying direct current of reverse polarity to wires 32 and 33 is complete, and this energy feeds over these wires to relay 2H so that contacts 35 and 36 of this relay establish the circuit of the yellow or caution lamp Y of signal 2S.

When the train vacates section 4T, track relay 4TR picks up and its contact 76 is closed so that alternating current is supplied from the secondary winding of transformer 3N over wires 50 and 25 to the primary winding of transformer 5N, 60 but as contact 82 of relay 6TR is open, energy is not supplied from the secondary winding of this transformer.

When track relay 4TR picks up, its contact 75 is closed to permit energy to be supplied to relay 4H, while its contact 77 interrupts the connection controlled thereby for supplying energy to relay 4SR, but as long as relay 4H is released, energy continues to be supplied to relay 4SR over the back contact 78 of relay 4H. Accordingly, contact 80 of relay 4SR remains picked up and maintains the circuit for supplying direct current of reverse polarity to wires 32 and 33.

When the train vacates section 5T, track relay 75 5TR picks up and its contact 100 establishes the

circuit of relay 5H, while its contact 101 is closed so that direct current of reverse polarity is supplied over line wires 24 and 25 to relay 4H and contacts 26 and 27 of this relay establish the circuit of the yellow or caution lamp Y of signal 4S. In addition, contacts 28 and 29 of relay 4H change the energy supplied to wires 32 and 33 from reverse to normal polarity, while contact 18 of relay 4H interrupts the circuit of relay 4SR and this relay releases.

When contact 101 of relay 5TR is picked up, the circuit of the secondary winding of transformer 6N is complete so that energy is supplied from this transformer over wires 24 and 25 to the primary winding of transformer 4N. As pointed out above, at this time energy is supplied to transformer 8M over the circuit controlled by contact 95 of relay 8SR, while energy is supplied from transformer 8M over line wires 14 and 15 to transformer 6N.

On the supply of energy to transformer 4N energy is supplied therefrom over line wires 32 and 33 to transformer 2N from which it is supplied through the rectifier to relay 27 to pick up contact 37 of the relay. As a result on the supply of direct current of normal polarity to line wires 33 and 32 and consequent movement of the polar contact 36 of relay 4H to its left-hand or normal position, the circuit including front contact 37 of relay 2J is established to light the green or clear lamp G of signal 2S.

As a result of the supply of energy of normal polarity to relay 5H the contacts 52 and 53 of this relay establish the circuit of the green lamp G of signal 5S, while contacts 54 and 55 of the relay are picked up to establish the connections over which direct current of normal polarity is supplied to wires 57 and 15 after picking up of relay 6TR.

When the train vacates section 6T, track relay 6TR picks up, while when the train vacates section 7T, track relay 7TR picks up so that its contact establishes the circuit of the relay 1H, while its contact 89 interrupts the connection of the secondary winding of transformer 8M directly across the wires 14 and 15 and connects this winding in series with the direct current source so that alternating current together with direct current of reverse polarity is supplied to wires 14 and 15. The direct current is supplied to relay 6H with the result that its contacts 17 and 18 establish the circuit of the yellow lamp Y of signal 6S, while contact 85 of relay 6H interrupts the circuit of relay 6SR, and contacts 20 and 21 of relay 6H cause direct current of normal polarity to be supplied to wires 24 and 25 so that contact 27 of relay 4H shifts to its left-hand or normal position and establishes the circuit of the green or clear lamp G of signal 4S.

In addition, on picking up of the contacts of relay 7TR its contact 93 establishes the circuit of the relay 1H and contacts 59 and 60 of this relay establish the circuit of the green lamp G of signal 7S.

When the train advances far enough to cause energy to again be supplied to the relay 8H, the contacts of this relay pick up so that its contacts 10 and 11 cause the direct current supplied to line wires 14 and 15 to be of normal polarity, while its contact 91 interrupts the circuit of relay 8SR and its contact 40 establishes a circuit to supply alternating current to the primary winding of transformer 8M.

From the foregoing it will be seen that when an eastbound train approaches the east end of passing siding 1T, relay 1H is released and cuts

off the supply of alternating current to transformer 1M so that energy is not supplied to relay 1J at the other end of the single track stretch and thus prevents the display of a clear indication by that signal. At this time, if the portion of the main track adjacent siding 2PS is vacant, alternating current energy is supplied to transformer 8M and is supplied therefrom to relay 2J so that signal 2S displays its clear indication.

When the eastbound train enters the single track stretch, the signals in the rear of the train are controlled so as to warn a following train of the presence of the first train. When the train advances beyond signal 4S, direct current of reverse polarity is supplied to line wires 32 and 33 and signal 2S displays its yellow or caution indication. When the train advances beyond signal 6S, direct current of reverse polarity is supplied to relay 4H, and signal 4S is caused to display its caution indication, while the direct current supplied to wires 32 and 33 is changed to normal polarity. In addition, when the train is in advance of signal 6S, alternating current is supplied from transformer 8M through transformers 6N, 4N, and 2N to the relay 2J so that the signal 2S will display a clear indication and thus permit a following train to proceed without reducing speed.

Furthermore, it will be seen that when the eastbound train advances into section 8T so that relay 8H releases, the supply of alternating current to the transformer 8M is maintained by the circuit established by contact 95 of relay 8SR so that the relay 2J will be maintained picked up to cause the signal 2S to provide its clear indication.

The operation of the equipment on movement of a westbound train through the track stretch is similar to that for movement of eastbound trains and will not be traced in detail. When the westbound train advances close enough to the west end of passing siding 2PS to cause release of relay 8H, the supply of alternating current to transformer 8M is cut off, and accordingly relay 2J releases to prevent the display of a clear indication by signal 2S and to cause this signal to provide its yellow or caution indication.

When the westbound train advances beyond signal 3S, alternating current is again supplied through the transformers 3N, 5N, and 7N, and the relay 1J is picked up to permit the display of the clear indication by signal 1S, while after the train advances into section 1T and causes release of relay 1H, the supply of alternating current is maintained by the circuit established by contact 65 of relay 1SR so that relay 1J is maintained picked up to maintain the display of the clear indication by signal 1S.

It will be seen, therefore, that when the portion of the main track opposite either of the passing sidings is occupied by a train approaching the single track stretch, the headblock signal at the other end of the single track stretch is prevented from displaying its clear indication. Accordingly, if a train passes that headblock signal and enters the single track stretch, it will do so at reduced speed and will be able to stop before colliding with the train moving in the opposite direction which entered the single track stretch at the other end.

Although I have herein shown and described only one form of railway signaling system embodying my invention, it is understood that various changes and modifications may be made therein within the scope of the appended claims

without departing from the spirit and scope of my invention.

Having thus described my invention, what I claim is:

1. In combination, a stretch of railroad track having a first and a second passing siding which are connected by a single track portion over which traffic moves in both directions, the rails of the single track portion being divided by insulated joints into a plurality of successive block sections, each block section having at the end thereof nearest the first passing siding a signal governing entrance of trains moving from the first to the second passing siding into the block section, the signals each being capable of displaying a plurality of indications, the signal for the block section adjacent the first passing siding being capable of providing a clear indication and at least one restrictive indication, each section having means governed by traffic conditions in said section and controlling the signal for such section, and means responsive to occupancy of the portion of the track stretch beside the second passing siding and controlling the signal for the block section adjacent the first passing siding in such manner as to permit the display of the clear indication by said signal only when the portion of the track stretch beside the second passing siding is vacant or is occupied by a train entering said track portion from the single track portion.

2. In combination, a stretch of railroad track having a first and a second passing siding which are connected by a single track portion over which traffic moves in both directions, a first signal at the end of the single track portion adjacent the first siding and a second signal at the end of the single track portion adjacent the second siding, said signals controlling entrance of trains into the single track portion and each being capable of displaying a stop, a clear, and at least one restrictive proceed indication, a first control means governed solely by traffic conditions in said single track portion for at times causing said first signal to display its stop indication, at other times to display a restrictive proceed indication, and at still other times to permit said first signal to display its clear indication, means responsive to traffic conditions in the portion of the track stretch beside the second passing siding and cooperating with said first control means to cause said first signal to display its clear indication only when the portion of the track stretch beside the second passing siding is vacant or is occupied by a train entering said track portion from the single track portion, a second control means governed solely by traffic conditions in said single track portion for at times causing said second signal to display its stop indication, at other times to display a restrictive proceed indication, and at still other times to permit said second signal to display its clear indication, and means responsive to traffic conditions in the portion of the track stretch beside the first passing siding and cooperating with said second control means to cause said second signal to display its clear indication only when the portion of the track stretch beside the first passing siding is vacant or is occupied by a train entering said track portion from the single track portion.

3. In combination, a stretch of railroad track having a first and a second passing siding which are connected by a single track portion over which traffic moves in both directions, the rails

5 of the single track portion being divided by insulated joints into a plurality of successive block sections, each block section having at the end thereof nearest the first passing siding a signal governing entrance of trains moving from the first to the second passing siding into the block section, the signals each being capable of displaying a plurality of indications, the signal for the block section adjacent the first passing siding being capable of providing a clear indication and at least one restrictive proceed indication, each block section having a pair of conductors governed by traffic conditions in said section and having electroresponsive means energized over the conductors for said section, each such electroresponsive means being responsive to energy of one character and controlling the signal for the associated block section, means governed by traffic conditions in the portion of the track stretch beside the second passing siding for supplying energy of a second character to the conductors for the block section adjacent said passing siding, the conductors for each block section except the section adjacent the first passing siding having associated therewith means effective on the supply thereto of energy of said second character to cause energy of said second character to be supplied to the conductors for the block section adjoining on the side nearest the first passing siding, and means responsive to the supply of energy of said second character to the conductors for the block section adjacent the first passing siding and governing the display of the clear indication by the signal for said block section.

4. In combination, a stretch of railroad track having a first and a second passing siding which are connected by a single track portion over which traffic moves in both directions, the rails of the single track portion being divided by insulated joints into a plurality of successive block sections, each block section having at the end thereof nearest the first passing siding a signal governing entrance of trains moving from the first to the second passing siding into the block section, the signals each being capable of displaying a plurality of indications, the signal for the block section adjacent the first passing siding being capable of providing a clear indication and at least one restrictive proceed indication, each block section having a pair of conductors governed by traffic conditions in said section and having electroresponsive means energized over the conductors for said section, each such electroresponsive means being responsive to energy of one character and controlling the signal for the associated block section, means effective when and only when the portion of the track stretch beside the second passing siding is vacant or is occupied by a train entering said track portion from said single track portion for supplying energy of a second character to the conductors for the block section adjacent said second passing siding, the conductors for each block section except the section adjacent the first passing siding having associated therewith means effective on the supply thereto of energy of said second character to cause energy of said second character to be supplied to the conductors for the block section nearest on the side adjacent the first passing siding, and means responsive to the supply of energy of said second character to the conductors for the block section adjacent the first passing siding and governing

the display of the clear indication by the signal for said block section.

5. In combination, a stretch of railroad track having a first and a second passing siding which are connected by a single track portion over which traffic moves in both directions, the rails of the single track portion being divided by insulated joints into a plurality of successive block sections, each block section having at the end thereof nearest the first passing siding a signal governing entrance into the block section of trains moving from the first to the second passing siding, the signals each being capable of displaying a plurality of indications, the signal for the block section adjacent the first passing siding being capable of providing a clear indication and at least one restrictive proceed indication, each block section having a pair of conductors governed by traffic conditions in said section, means for supplying direct current to the conductors for each section, each section having a direct current relay energized over the conductors for such section and controlling the signal for such section, means effective when and only when the portion of the track stretch beside the second passing siding is vacant or is occupied by a train entering said track portion from said single track portion for supplying alternating current energy to the conductors for the block section adjacent the second passing siding, the conductors for each block section except the block section adjacent the first passing siding having associated therewith means effective on the supply of alternating current thereto to cause alternating current to be supplied to the conductors for the block section adjoining on the side nearest the first passing siding, and means responsive to the supply of alternating current to the conductors for the block section adjacent the first passing siding and

governing the display of the clear indication by the signal for said block section.

6. In combination, a stretch of railroad track having a first and a second passing siding which are connected by a single track portion over which traffic moves in both directions, the rails of the single track portion being divided by insulated joints into three block sections including a first block section adjacent the first passing siding, a second block section adjacent the second passing siding, and an intermediate block section located between said first and second block sections, each block section having at the end thereof nearest the first passing siding a signal governing entrance into the block section of trains moving from the first to the second passing siding, the signals each being capable of displaying a clear, a caution and a stop indication, the signals for the intermediate 15 and second sections being governed by traffic conditions in the associated section, the signal for the first section being governed by traffic conditions in said first section and in the intermediate section in such manner that the signal 20 displays its stop indication when said first section is occupied, its caution indication when said first section is vacant and the intermediate section is occupied, and its clear indication when the first and intermediate sections are both 25 vacant, and means responsive to occupancy of the portion of the track stretch beside the second passing siding for controlling the signal for said first section to permit the display of a clear indication by said signal only when the portion 30 of the track stretch beside the second passing siding is vacant or is occupied by a train entering said track portion from the single track portion.

GEORGE R. PFLASTERER.

CERTIFICATE OF CORRECTION.
Patent No. 2,344,324. March 14, 1944.
GEORGE R. PFLASTERER.

It is hereby certified that error appears in the printed specification of the above numbered patent requiring correction as follows: Page 6, second column, lines 71 and 72, claim 4, for "nearest on the side adjacent" read --adjoining on the side nearest--; and that the said Letters Patent should be read with this correction therein that the same may conform to the record of the case in the Patent Office.

Signed and sealed this 23rd day of May, A. D. 1944.

Leslie Frazer
(Seal) Acting Commissioner of Patents.
